UNITED STATES PATENT OFFICE.

WILLIAM HUDDLESTON BARR, OF GROVE SPRING, MISSOURI.

FIRE-ESCAPE.

SPECIFICATION forming part of Letters Patent No. 328,637, dated October 20, 1885.

Application filed May 23, 1885. Serial No. 166,484. (No model.)

To all whom it may concern:

Be it known that I, WILLIAM HUDDLESTON BARR, of Grove Spring, in the county of Wright and State of Missouri, have invented an Improved Fire-Escape, of which the following is a specification.

The special object of this invention is to improve step-rod escape-ladders so that all the step-rods will be connected together on both sides, and thus re-enforce them to avoid the danger of breakage. When people are in danger, and in a high state of excitement, a sure footing is required and a convenient side hold for their hands.

15 In order to accomplish these objects, I adopt means which will first be described in connection with the drawings, and then clearly pointed out in the claim.

Figure 1 of the drawings is a perspective view showing the life-escape applied to the side or end of a residence or other building. Fig. 2 is a vertical section showing the location and attachment of the rods with respect to the house.

25 In the drawings, A represents the step-rods carrying at each end a staple, a, which are integral with the rods, and are driven into the house side or end in any suitable or well-known way.

B represents a wire which may be as large 30 or larger than an ordinary telegraph-wire, and is wound around the step-rods at the angles a' so as to connect and cause them to serve as a mutual support to one another. There is preferably one on each side, and extending from 35 top to bottom, as clearly shown in Fig. 1 of the drawings. These side wires not only connect and greatly strengthen the foot-hold, but they also afford a very convenient hand-hold and effectually prevent the fingers of one person 40 from being mashed by another who is coming down after him.

With my present improvement the step-rod fire-escape is cheap, simple, and thoroughly effective.

45 Having thus described all that is necessary to a full understanding of my invention, what I claim as new, and desire to protect by Letters Patent, is—

A fire-escape ladder consisting of the steps 50 A a a, connected at the angles a' by the wires B B, wound around them, substantially as shown and described.

WILLIAM HUDDLESTON BARR.
